UNITED STATES PATENT OFFICE.

JOHN ADDISON AND WILLIAM ADDISON, OF HAMILTON, ONTARIO, CANADA.

CLOTHES-MANGLE.

SPECIFICATION forming part of Letters Patent No. 369,675, dated September 13, 1887.

Application filed January 31, 1887. Serial No. 226,105. (No model.)

To all whom it may concern:

Be it known that we, JOHN ADDISON and WILLIAM ADDISON, of the city of Hamilton, in the county of Wentworth, in the Province 5 of Ontario, in the Dominion of Canada, have invented certain new and useful Improvements in Clothes-Mangles, of which the following is a specification.

Our invention relates to wooden mangles; 10 and our improvements consist in the manner in which the rollers are fixed in the frame and the compression brought on them by screw-bolts, and the device for fixing the mangle up against the wall, closing it up, and holding it 15 in a compact space when not in use, and readily letting it out and having it ready for use, as hereinafter described and claimed.

In the accompanying drawings, Figure 1 is 20 a front view of the mangle. Fig. 2 is a side view of the same, showing it closed up against the wall when not in use. Fig. 3 is also a side view of the mangle, showing it opened out from the wall and ready for use.

K is a board or other fixed support permanently secured to the wall and provided with the eyes x at the top and the brackets m near the bottom. The mangle-frame consists of the side bars, E and F, each provided with suitable cross-braces and pivoted together by the 30 hinges P at the bottom. The side bars, F, are pivoted to the brackets m by the pins m', near their lower ends, and the said bars have the levers L pivoted to them, each provided with a long and a short end furnished, respectively, 35 with the hooks n and o, which engage with the said eyes x from above and below, as shown in the drawings, and thereby hold the side bars, F, parallel with the wall, or at an angle with the same, with the lower ends of the side 40 bars, F, resting against it.

A are the mangle-rollers secured upon the shafts c, journaled in side bars, E and F, which are strengthened by the addition of pieces W at the top to better support the said shafts.

45 One of the shafts is provided with the han-

dle D, which has a split end, d, and is secured to the shaft by the bolt d'. The two rollers are caused to revolve simultaneously by the gear-wheels B, secured to them by dowel pins b, or otherwise caused to turn with the shafts. 50

The pressure of the rollers is regulated by the thumb-nuts J, which work upon the screwed ends of the bolts g, which are provided with square heads g' let into the side bars, F, at the back, and with square washers g'', let into the side bars, E, at the front, for the said thumb-nuts to bear against. 55

T is a table pivotally connected to the side bars, E, at the top by the hinges t, so that it may be folded over the top of the rollers when the mangle is not in use; and y are supporting-levers pivoted to the said table at one end and sliding in the guides V when the table is turned on its hinges. When the table is turned, as shown in Fig. 3, these levers rest upon the 65 handle-shaft c and the top part of the said guides, and thereby support the table. 60

What we claim is—

1. The combination of a support secured to a wall, a mangle-frame pivotally connected to the lower part of the said support, and the lever L, provided with ends of unequal length 70 provided with hooks o and n, pivoted to the mangle-frame and engaging with the upper part of the said support, substantially as set 75 forth.

2. The combination, with a mangle-frame provided with side bars, E and F, pivotally connected at their lower ends, of the table T, pivoted to side bars, E, the guides V projecting from side bars, F, the rollers journaled upon shafts in the upper part of the frame, and the supporting-levers y, pivoted to the table, substantially as and for the purpose set forth. 80

JOHN ADDISON.
WM. ADDISON.
